METERING FLUID FEEDING DEVICE

Charles James Eacock and Claude H. Clauser,
Kansas City, Mo.; Celeste H. Clauser administratrix
of said Claude H. Clauser, deceased

Application October 6, 1928. Serial No. 310,899

16 Claims. (Cl. 184—7)

Our invention relates to improvements in fluid feeding devices and more particularly to means for feeding a fluid such as a lubricating medium under pressure automatically in direct proportion to the movement of the operating parts of a member with which the device is associated, and is particularly an improvement over the fluid feeding devices disclosed in our application for Patent Serial No. 251,881, filed February 4, 1928.

It is a purpose of our invention to provide fluid feeding means of the above mentioned character that is particularly adapted for use as a lubricating device and which is so constructed as to economize on the amount of lubricant dispensed to each of the parts to be lubricated by supplying the proper amount of lubricant to the parts but not a needless excess and which can be made at a relatively small cost.

Our invention comprises a comparatively simple construction which is strong and durable and which is automatic in operation, feeding or supplying the lubricant or other fluid in direct proportion to the movement of the parts of the mechanism with which the same is associated. It is furthermore an object of the invention to provide a device of this character that is adapted to be associated with a reservoir or other container for lubricant or other fluid and to use a plurality of said feeding devices obtaining the supply of lubricant from a common reservoir to lubricate a plurality of parts with lubricant from the same reservoir.

It is a further object of this invention to provide new and improved means for producing the reciprocatory movement of the feeding member, the movement being initiated by the moving part or parts of the member with which the feeding device is associated, the reciprocatory movement of the feeding member being proportional to the movement of the parts with which the device is associated.

The means for producing the reciprocatory movement of the feeding member is so constructed that the actuating mechanism for producing a measured movement of the feeding member in proportion to the movement of the parts with which the device is associated is positive in operation so that even a small movement of the parts will produce a corresponding movement of the actuating mechanism. The positive operation of said actuating mechanism is obtained due to the provision of a novel clutch mechanism responsive to extremely small movement of the parts with which the same is associated. This clutch mechanism is furthermore simple in con-

struction and is so made that metal stampings may be used for the parts thereof, whereby a low cost of manufacture results.

Our improved feeding device is also adapted for operating in other positions than an upright position and is so constructed that all the moving parts are engaged by the fluid which may be utilized to lubricate the same.

It is a further purpose of our invention to provide a fluid feeding device of the above mentioned character that is so constructed that the feeding device, itself, may be used as a swivel connection in a pipe line where all the fluid feeding devices are supplied with a fluid, such as lubricant, from a central reservoir. In this form of the invention the one pipe connection of the joint is made with the casing member of the device and the other pipe connection of the joint is made with the base member of the device.

The feeding mechanism used in this form of the invention is of a type that is now preferred and which is of universal application, being adapted to be used with a single fluid feeding device that has no connection with any other fluid feeding device, as well as with the type of fluid feeding device forming the swivel joint or in any other fluid feeding device adapted for use in connection with a piping system leading from a central source of supply. In this form of the invention the operating mechanism has been standardized so that only slight variations therein are necessary to adapt the same to all the uses thereof, and the principal difference between the different applications thereof is in the external connections provided.

It is an important purpose of our invention to provide a fluid feeding system such as a lubricating system in which the lubricant is distributed from a central reservoir to the various points at which the lubricant is to be fed to the parts to be lubricated and in which the lubricant is distributed to such points at a low pressure and fed to the parts to be lubricated at a high pressure. More particularly our invention comprises a lubricating system in which the lubricant is piped from a reservoir to the parts that are to be lubricated by gravity or at a low pressure and supplied to our improved feeding devices which feed the lubricant at a high pressure to the parts to be lubricated, thus providing a system in which there is no high pressure distribution whatsoever.

By providing the individual feeding devices a further advantage is obtained, whereby a system may be provided in which the lubricant is sup-

plied, through a piping system, at substantially a uniform very low pressure and is fed to the parts to be lubricated at different much higher pressures, depending upon what pressure may be 5 needed at the parts to be lubricated. The amount of lubricant supplied for a given movement of the parts may also be varied in accordance with the requirements, and the feeding device may be adjusted to give the desired pressure at the 10 outlet thereof by varying the tension on the springs therein or the size thereof and by varying the feeding stroke or size of the plunger. Thus, each individual feeding device may have its spring means and plunger arranged so as to 15 obtain the desired amount and pressure of lubricant with each feeding stroke.

Other objects and advantages of our invention will appear as the description of the drawings proceed. We desire to have it understood, 20 however, that we do not intend to limit ourselves to the details of structure shown or described, but that we intend to include as part of our invention all such obvious changes and modifications of parts as would occur to a person skilled in this art and as would fall within 25 the scope of the claims.

In the drawings:

Fig. 1 is a longitudinal sectional view through one form of our improved fluid feeding device. 30 Fig. 2 is a similar view thereof taken at right angles to Fig. 1, substantially on the line 2—2 of Fig. 1, the follower bar being shown in elevation.

Fig. 3 is a section taken on the line 3—3 of 35 Fig. 2.

Fig. 4 is a section taken on the line 4—4 of Fig. 2.

Fig. 5 is an end view on a smaller scale of the feeding device as viewed from the lower end of 40 Fig. 2.

Fig. 6 is a side view thereof.

Fig. 7 is a side elevation of the cam.

Fig. 8 is a perspective of the plunger rod detached.

45 Fig. 9 is a longitudinal sectional view similar to Fig. 2 through another form of our improved fluid feeding device, showing the type of feeding mechanism at present preferred.

Fig. 10 is a section taken on the line 10—10 of 50 Fig. 9.

Fig. 11 is a longitudinal sectional view similar to Fig. 2 of a modification of the structure shown in Fig. 9.

Fig. 12 is a section taken on the line 12—12 of 55 Fig. 9.

Fig. 13 is a diagrammatic view of a portion of the steering mechanism of an automobile, showing our improved lubricating system applied thereto.

60 Fig. 14 is a fragmentary view partly in section and partly in perspective of the steering pitman arm, drag link and adjoining parts of the steering mechanism and frame of an automobile showing our improved lubricating system applied 65 thereto.

Fig. 15 is a fragmentary view in elevation of the steering lever, and knuckle and associated parts.

70 Fig. 16 is a view taken substantially at right angles to Fig. 15, the front axle being shown in vertical section.

Fig. 17 is a fragmentary elevation of the front end of the drag link and the steering lever, and

75 Fig. 18 is a diagrammatic view illustrating the variation in pressures and quantity of lubricant

that may be supplied to various parts from the same low pressure supply.

Referring in detail to the drawings, in Figs. 1 to 8, inclusive, showing one form of our invention, a fluid feeding device is shown which comprises a casing 20 of cup-like form having an integral end wall 21 and having a disk-like member 22 secured thereto by crimping the edges of the cup-like member 20 around the circumferential edge of the member 22 to clamp said edge in the groove 23 formed by the outwardly directed offset 24 and the inturned flange 25 provided on the casing member 20. A base member 26, having an externally screw-threaded portion 27 thereon for connection with any suitable device that is to be lubricated, is provided to cooperate with the casing 20. The base member 26 is provided with an enlargement 28 having flat faces thereon for engagement by means of a wrench or other tool for turning the same. Said member 26 is provided with a hub portion 29 and the disk-like member 22 is provided with an annular portion 30 that is rotatably mounted on the hub portion 29. Inwardly of the hub portion 29 is a smaller hub portion 31 and the said member 26 terminates at the end thereof in an externally screw-threaded portion 32 upon which the tubular guide member 33 is screw-threadedly mounted.

A driving clutch disk 34 is mounted on the closure disk 22 to rotate or oscillate therewith, being pressed upon the annular flange 30, said clutch disk 34 being shown more in detail in Fig. 4 and being provided with the curved cam faces 35 which are curved on a gradually decreasing radius of curvature from the periphery of the disk 34 to the shoulders 36 thereon. A cam member 37 which is made up of a cylindrical wall portion 38 and a cam surface forming flange 39 is mounted in the casing 20 and the ball members 40 are mounted between the cylindrical wall portion 38 of said cam member 37 and the cam faces 35 of the clutch disk 34. Coil springs 41 are mounted between the balls 40 and the shoulders 36.

Referring to Fig. 4, it will be seen that inasmuch as the surface 35 approaches the member 38 in a clockwise direction, rotation of the disk in a counter-clockwise direction will wedge the balls 40 between the cylindrical wall portion 38 of the clutch member 37 and the cam face 35 of the disk 34, the balls being held in position ready for engagement with the member 38 by the springs 41. As a result a counter-clockwise movement of the disk-like member 34 will immediately cause the cam member 37 to be carried along with the disk-like member 34 in a counter-clockwise direction.

The holding clutch disk 42 is mounted in fixed position on the hub portion 31 by a pressing operation and is furthermore held in such position by the clamping engagement of the end wall of the tubular guide member 33 with the holding clutch disk 42. The disk 42 is shown more in detail in Fig. 3 and is provided with curved cam faces 43 similar to the faces 35 on the disk 34 and with shoulders 44 corresponding to the shoulders 36 on the disk 34. The holding clutch disk 42 is mounted within the cam member 37 and the balls 45 are mounted between the cylindrical wall portion 38 of the cam 37 and the cam faces 43 on the disk 42, being held in engagement with the faces 43 and the cylindrical portion 38 by means of the coil springs 46 mounted between the shoulders 42 and the balls. The disk 42 being stationary or fixed relatively to the member 26,

any tendency of the cam member 37 to rotate in a clockwise direction will cause the balls 45 to wedge between the cylindrical wall portion 38 and the cam faces 43 to hold said cam member from such clockwise rotation.

It will accordingly be seen, that a rotation relative to the member 26 of the casing 20 in a counterclockwise direction will move the cam member 37 in the same direction through the same arc as the member 20 relative to the member 26 but the rotation of the casing 20 in a clockwise direction will not cause the cam member 37 to move at all, whereby the cam member 37 will move in exact proportion to the movements of the casing 20 relative to the base member 26 whether the relative movement is an intermittent or a constant rotation or an oscillation. The ball and disk clutch members will respond to even the slightest movement of the parts to cause the cam 20 to move with the driving disk 34 in one direction and will be held from any movement, whatsoever, with the driving disk 34 relative to the holding disk 42 in the opposite direction.

A washer 47 is mounted between the disks 34 and 42 to hold the balls 40 and 45 and the springs 41 and 46 in position and a, preferably, metallic washer 48 is mounted within the cam member 37 to hold the balls 45 in position. The washer 48 is associated with a wire screen member 49 which is flanged at 50 to receive the washer 48 snugly within the same, said washer and screen member being pressed into the cylindrical portion 38 of the cam 37 to hold the same in position therein so that the screen 49 and the washer 48 will rotate with the cam member 37. The member 22, the disk 34 and the washer 47 are thus confined between the enlargement 28 on the member 26 and the disk 42. Said screen member 49 is provided with a flange portion 51 embracing the tubular guide member 43 and rotatable thereon. A fiber washer 52 is also provided between the member 26 and the closure disk 22 to form a fluid tight joint between the same.

The cam member 37, (see Fig. 7) is slit at diametrically opposite points of the flange portion 39 and the flange portion is formed so as to provide inclined cam faces 53 that lie diametrically opposite each other and extend upwardly from a low point 54 adjacent the abrupt shoulder 55 formed at the slit portion of the flange to a high point 56 adjacent the diametrically opposite abrupt shoulder 55. Thus the cam surface provides two gradually inclined faces 53 arranged diametrically opposite each other and two abrupt shoulders 55 forming duplicate cam members.

The tubular guide member 33 is provided with a pair of oppositely arranged slots 57 through which the cross-bar extends. The cross-bar 58 is a sheet metal member that serves as a follower engaging with a cam and which may accordingly be termed a follower bar. The opposite ends of the bar 58 are cut away to form shoulders at 59 with which the coil spring 60 of relatively large size engages at one end thereof. The other end of the spring engages the end wall 21 of the casing 20 and also engages the closure or valve member 61 having the offset valve or closure portion 62 provided thereon, aligning with the opening 63 in the end wall 21, said opening 63 being provided in an outwardly offset portion of the end wall 29 having a conical wall portion 64 with which the correspondingly shaped conical wall portion 65 of the closure 61 engages, due to the pressure of the spring 60, to close the opening 63 fluid tight but permitting introduction of fluid

through the opening 63 by any suitable means. The spring 60 also urges the cross-bar 58 into engagement with the cam surface 53, said cross-bar or follower-bar being provided with projecting straight foot portions 66 engaging with the flange 39 on the cam.

The member 26 is provided with a bore 67 slidably receiving the plunger rod 68, said plunger rod 68 being provided with a head 69 thereon that is cylindrical in transverse section so as to be slidably received in the cylindrical bore in the tubular guide member 33. The upper and lower surfaces 70 of the head 69 are curved on portions of spheres and the following bar 58 is provided with an opening 71 therein which is curved on the same arcs as the upper and lower surfaces of the head both lengthwise and crosswise thereof, as will be clear from Figs. 1 and 2. The head 69 is mounted within the opening in the bar 58 and any movement of the bar 58 in the direction of the axis of the plunger 68 will be transmitted to the plunger 68.

Thus as the follower bar 58 is moved gradually toward the end wall 21 as the foot portions 66 thereof move upwardly along the inclined cam faces 53 during rotation of the cam 37 the plunger 68 is moved upwardly an amount in proportion thereto. Such movement may be continuous or intermittent, depending upon the amount of movement of the casing 20 relative to the base member 26, but, in any event, this movement will continue until the highest point on the cam faces 53 is reached, whereupon the member 58 will drop off the shoulders 55 with a snap action due to the spring 60 and the plunger 68 will be moved in a downward or feeding direction by snap action. The movement of the plunger is thus in direct proportion to the movement of the member 20 relative to the member 26 during the return stroke thereof and a substantially instantaneous operation during the feeding stroke thereof. The number of feeding movements of the plunger will accordingly be directly proportioned to the movement of the member 20 relative to the member 26 and the fluid fed due to the movement of the plunger 68 will be measured in proportion to the movement of the member 20 relative to the member 26.

The screen member 49 serves as a self-cleaning rotatable filtering means for the fluid, such as lubricant, to be fed by the device. The said fluid is contained within the casing 20 and is in engagement with all the working parts of the device to lubricate the same. The disk 42 is provided with an opening 72 and the washer 47 is provided with a central opening 73 overlapping the same. The opening 72 also aligns with an opening 87 communicating with the transverse bore 74 provided in the member 26, said transverse bore communicating with a cylindrical passage 75 in the base member 26 into which the plunger rod 68 is projected when the member 58 drops off the shoulders 55, said rod 68 having a sliding fit in the passage 75.

The passage 75 leads into a larger passage 76 in the base member 26 having a conical wall 77 therein against which the ball valve member 78 seats, said ball valve member being held in engagement with the seat by means of the coil spring 79 held under compression between the ball 78 and the inwardly directed flange 80 on the member 26. By providing the longitudinally and transversely curved surfaces 70 on the head 69 of the plunger and the correspondingly curved surfaces 71 on the follower bar 58, the follower

bar 58 is adapted to rock slightly to permit both of the foot portions 66 to drop off the shoulders 55, if one of said foot portions drops off one of said shoulders, thus ensuring the snap action of 5 the device.

The rotation of the member 20 may be accomplished in any desired manner and in Figs. 1, 2, 5 and 6 an arrangement accomplishing this is shown. The means shown comprises a ring-like member 81 which is made angular in cross section to provide a flange 82 and is provided with fingers 83 which are adapted to be bent around and clinched to the offset portion 24 of said casing to firmly secure the ring 81 on the 10 casing so as to rotate therewith, said fingers before being clinched being adapted to pass over the offset 24. The ring 81 is further provided with an outwardly directed arm 84 stamped from the same piece of metal as the ring 81, which is 15 connected with any desired member that moves relative to the bearing member or other member to which the base member 26 may be secured. Any movement of the arm 84 will move the ring 81 and carry the casing therewith.

Referring now to Figs. 9, 10 and 12, the form 20 of the invention shown therein comprises a casing 120 of a cup-like form having an integral end wall portion 121 and having a disk-like closure member 122 secured to the casing 120 by 25 clamping the edges thereof along the circumferential edge of the member 122, to clip said edge in the groove 123 formed by means of the outwardly directed off-set 124 and the inturned flange 125 provided on the casing member 120.

A base member 126 is provided with an externally 30 screwthreaded portion 127 thereon for connection with any suitable device that is to be lubricated, said base member cooperating with the casing 120. Mounted within the base member 40 126 is a tubular member 128 upon which the sleeve 129 is mounted in fixed position. The disk-like member 122 is somewhat dished in form and is provided with an inturned annular flange portion 130, rotatably mounted on the sleeve 129. The tubular member 128 is provided with a lateral 45 opening 131 above the bearing sleeve 129 and with a tubular upper end portion 132 extending upwardly therefrom. The enlargement 131 is provided with a lateral opening 50 133 therein.

A ring-like driving clutch disk 134 is mounted in fixed position on the casing 120, being clamped in the groove 123 along with the disk 122. The driving clutch disk 134 is shown more in detail in Fig. 10 and is provided with curved cam faces 55 135 formed in the inner edge thereof, said cam faces 135 being curved on a gradually decreasing radius of curvature from a point nearest the inner edge of the disk 134 adjacent the shoulders 136 to a point the farthest from said inner edge at the shoulders 136'. A cam member 137 is provided, which is made up of the cylindrical wall portion 138 having a cam surface provided on the edge portion thereof and a flange 139 extending inwardly from said cylindrical portion 138. Ball members 140 are mounted between the cylindrical wall portion 138 and the cam faces 135 of the clutch disk 134 and coil springs 141 are mounted between the ball members 140 and 60 the end walls 136' provided in the recesses formed in the inner periphery of the disk 134 to provide the cam faces 135.

Referring to Fig. 10 will be seen that in as 65 much as the surface 135 of each cam portion approaches the member 138 in a counter-clock-

wise direction, rotation of the disk 134 in a clockwise direction will wedge the balls 140 between the cylindrical wall portion 138 of the clutch member 137 and the cam faces 135 of the disk 134, the balls being held in position ready for engagement with the member 138 by the springs 141. As a result, a clockwise movement of the disk-like member 134 will immediately cause the cam member to be carried along with the member 134 in a clockwise direction.

The flange 139 of the clutch member 137 is provided with recesses in the inner periphery thereof forming the cam faces 143 extending between the shoulders 142 and 144, the shoulders 142 corresponding to the shoulders 136 of the disk 134 and the shoulders 144 corresponding to the shoulders 136' on the disk 134. The cam faces 143 are thus inclined in an opposite direction to the cam faces 135 on the disk 134. Balls 145 are mounted between the bearing member 129 and the cam faces 143 on the flange 139, being held in engagement with the cam faces 143 and the cylindrical outer surface of the bearing member 129 by means of coil springs 146 mounted between the shoulders 144 and balls 145. As the cam surfaces 143 approach the bearing member 129 in a clockwise direction, any tendency of the cam member 137 to rotate in a counter-clockwise direction with the disk 144 will cause the balls 145 to wedge between the cylindrical outer wall portion of the bearing member 129 and the cam faces 143 to hold said cam members 137 from such counter-clockwise rotation.

It will accordingly be seen that a rotation relative to the base member 126 of the casing 120 in a clockwise direction will move the cam member 137 in the same direction through the same arc as the member 120 relative to the member 126, but the rotation of the casing 120 in a counter-clockwise direction relative to the base member 126 will not cause the cam member 137 to move at all, whereby the cam member 137 will move in a constant direction in exact proportion to the movement of the casing 120 relative to the base member 126, whether the relative movement is constant or intermittent in a predetermined direction or an oscillation. The ball and disk clutch members provided by the disk 134 and the flange 139 are responsive to even the slightest movement of the parts to cause the cam to move with the driving disk 134 in one direction and will be held from any movement whatsoever with the driving disk 134 relative to the bearing member 129 in the opposite direction.

The end of the bearing member 129 adjacent the lateral enlargement 131 in the tubular member 138 is bevelled as shown at 147 to permit the end portion of the member 129 to engage snugly with the bottom wall 148 of the enlargement 131, said wall portion 138 thus serving to hold the ball members 145 in position and locking the member 129 in fixed position between the member 126 and the wall 148. The washer 149, angular in cross-section, is provided upon the cylindrical portion 138 of the cam 137 to hold the balls 140 in position. The tubular member 128 is provided with transversely aligning openings 150 therein that align with the passage 151 in the base member 126, said passage 151 extending through the externally threaded tubular extension 152 on the base member 126.

The upper edge portion of the cylindrical cam portion 138 of the cam member 137 is formed so as to provide the inclined cam faces 153 that correspond to the cam faces 53 in the form 150

shown in Figs. 1 to 8, inclusive, except that the same are oppositely inclined, the same extending upwardly from a low point 154 to an abrupt shoulder 155 at the high point 156 thereof. Thus 5 the cam surface comprises two gradually inclined faces 153 that lie diametrically opposite each other and two abrupt shoulders 155 forming duplicate cam members.

The upper tubular end portion 132 of the tubular member 128 is provided with a pair of oppositely arranged slots 157 through which the bar 158 extends, said bar 158 corresponding to the bar 58 shown in Figs. 1 and 2 and being of slightly different shape. The bar 158 is of sheet metal and the opposite ends thereof are cut away to form shoulders at 159 with which the coil spring 160 of relatively large size engages at one end thereof. The other end of the spring 160 engages with the end wall 121 of the casing 120. 10 In the form of the invention shown in Fig. 9 no filler opening is provided in the casing 120 corresponding to that shown in Fig. 2 but instead a laterally extending externally threaded nipple 161 is provided on the casing 120 with which the pipe section 162 is connected by means of a union 163 of any standard construction. The bar 158 is provided with substantially straight projecting foot portions 164 engaging with the cam faces provided on the upper edge of the cylindrical portion 138 of the cam 137, being held 15 in engagement therewith by means of the coil spring 160, said cross bar thus serving as a follower bar or follower member engaging said cam.

Mounted within the tubular member 128 is a valve and pump body portion 165 having a head 166 on the outer end thereof and being provided with a bore 167 therein, slidably receiving the plunger rod 168, said plunger rod having a head 169 thereon corresponding to the head 69 on the plunger rod 68 and having curved surfaces 170 thereon engaging with the curved surface of the opening 171 in the follower bar 158, the wall of the opening 171 being curved to correspond with the curvature of the upper and lower end of the head 169 in the same manner as in the form shown in Figs. 1 to 8 inclusive, and having the same purpose as described in connection therewith.

As the head 169 is mounted within the opening 171 in the bar 158 any movement of the bar 158 in the direction of the axis of the plunger 168 will be transmitted to said plunger. Thus, as the follower bar 158 is moved gradually toward the end wall 121 as the foot portions 164 thereof move upwardly along the inclined cam faces 153 during the rotation of the cam 137, the plunger 168 is moved upwardly an amount in proportion thereto. This movement will continue in a manner described in connection with the form of the invention shown in Figs. 1 to 8 inclusive, until the highest points on the cam faces 153 are reached, whereupon the member 158 will drop off the shoulders 155 with a snap action due to the pressure of the spring 160 and the plunger 168 will be moved in a downward or feeding direction by snap action. The number of said movements of the plunger will accordingly be directly proportional to the movement of the member 120 relative to the member 126, as previously described in connection with the form of the invention shown in Figs. 1 to 8 inclusive, and the amount of fluid fed through the bore 167 due to the movement of the plunger 168 will be in proportion to the movement of the member 120 relative to the member 126.

The fluid is free to pass in either direction from the pipe 162 to the tubular projection 152 through the casing 120, and the tubular member 128, due to the provision of the openings 150 in the tubular member 128; the upper end portion 172 of the member 165 being reduced to provide an opening through the tubular member 128 around said member 165 to said openings 150. The reduced portion 172 of the member 165 is also provided with a transverse opening 174 aligning with the openings 150 and with a longitudinal bore 175 aligning with the bore 167, the opening 174 supplying fluid to the bore 175. The plunger rod 168 is projected into the bore 175 in which it has a sliding fit when the follower member 158 drops off the shoulders 155 of the cam to feed the fluid into the enlarged passage 176 in the member 165.

The passage 176 has a conical end wall 177 against which the ball valve member 178 seats, said ball valve member being held in engagement with said seat by means of the coil spring 179 held under compression between the ball 178 and the inwardly directed flange 180 on the member 165. The head 166 has a conical surface 181 thereon and the base member 126 is bevelled at 182, the tubular member 128 being swaged outwardly therebetween to firmly hold the members 126, 128 and 165 in assembled relation.

The rotation of the member 120 relative to the base 126 is accomplished due to relative movement of the pipe section 162, and the pipe section connected with the tubular member 152, the pipe section 162 and the member 126 being carried by two relatively movable parts with which the fluid feeding device is associated.

Referring now to Fig. 11 the internal structure of the device is exactly the same as in the form shown in Figs. 9, 10 and 12, except for certain minor changes referred to below, the principal parts of the device being standardized and being interchangeable no matter whether the device is used with a central reservoir and the pipe arrangement shown in Fig. 9, or some similar pipe arrangement with means for producing rotation of the casing relative to the base that is independent of the piping means such as is shown in Fig. 11, or whether the casing serves as an independent reservoir for the fluid to be fed. This latter arrangement is shown in Fig. 11, in which the casing 120' is similar to the casing 120, except that the filler opening 184 is provided in the outwardly off-set portion of the end wall 121 having the conical wall portion 185 with which the similarly shaped closure 130 member 186 mounted on the arm 187, engages due to compression of the spring 160, to close said opening. The base member 126' is merely provided with the longitudinal passage through the same into which the tubular member 128 fits, and is provided with an externally threaded nipple 127 for securing the base 126' to any device to which fluid such as lubricant is to be fed.

The structure of the actuating mechanism and feeding means in Fig. 11 is the same as in Figs. 9, 10 and 12, except that a plug 188, of fibrous material, is mounted in the upwardly extending portion 132 of the tubular member 128 and slidably receives the plunger rod 168. The purpose of providing the plug 188 is to prevent fluid from running out of the tubular member 132 from the enlargement 131 when the device is arranged with the axis of the plunger 168 in a horizontal direction. When the device is in such position the proximity of the cam member 137 to the en-

largement 131 will cause the fluid to be carried upwardly between the members 131 and 137 to be fed into the opening 133, the opening 133 being placed in an upward position when the device is horizontally arranged. In this form of the invention the rotation of the member 120 relative to the member 126 is accomplished by means of the ring-like member 81 having a flange 82 and the fingers 83 for securing the same to the off-set portion of the cup 120', the ring having the arm 84 thereon and operating to rotate the member 120' in a similar manner to that described in connection with the device shown in Figs. 1, 2, 5 and 6.

15 In all the forms of the invention described the ball and disk clutch members operate in the same manner to cause rotation of the cam member with the casing in one direction, upon even the slightest movement of the casing relative to the base member, and to hold said actuating cam member from rotation with the casing in a reverse direction, the holding means operating upon the slightest reverse rotation of the casing relative to the base. Thus a metering fluid feeding device is provided. Furthermore, due to the relatively small cross-section of the end of the plunger rod in all forms of the invention to the size of the spring utilized for projecting the same in a feeding direction, a very high pressure of the 30 fluid fed by means of the device will be obtained.

Referring now to Figs. 13 to 18 inclusive, in Fig. 13 the steering mechanism and the lubricating system of an automobile are shown diagrammatically, the central reservoir for the lubricant being designated by the numeral 190. The said reservoir is mounted at any convenient point on the automobile having the frame member 191, upon which the pitman arm 192 is mounted for swinging movement, said pitman arm being connected with the drag link 193 by means of a ball and socket joint having the socket member 194 provided on said drag link and the ball 194' provided on the pitman arm. The opposite, or front, end of the drag link has the steering lever 195 connected therewith, said lever 195 being connected by means of the link 196 with a similar lever 195' on the opposite side of the automobile. The lever 195 has the yoke 197 provided thereon carrying the stub axle 198, said yoke being pivotally mounted on the steering knuckle 199 provided on the front axle 200, as will be described more in detail below. The portion of the lubricant distributing system illustrated in Fig. 13, comprises a pipe 201 extending from the reservoir 190, and fixed relatively to the frame of the automobile, a pipe section 202 movable with the arm 192, and mounted thereon, a pipe section 203 mounted on and movable with the drag link 193, a pipe section 204 carried by and movable with the lever 195, and having a branch 205 leading to the other side of the automobile through the pipe 206 carried by and movable with the link 196. As the piping system on both sides of the automobile used to lubricate the steering mechanism is duplicated, only that on the one side thereof will be here referred to, the pipe 207 being carried by the yoke 197 which is a part of the lever 195 and thus being fixed relatively to the pipe 204, and the piping system on the opposite side of the automobile being provided with pipes corresponding to the pipes 204 and 207 referred to, as will be evident from Fig. 13.

Referring now to Fig. 14, it will be seen that the pipe section 201 is connected with the casing portion 208 of one of the fluid feeding devices

such as previously described, and that the pipe section 202 is connected with the base portion 209 of said feeding device, said base portion being mounted on the shaft 210 upon which the arm 192 is non-rotatably mounted, said shaft rotating in the bearing 211. The fluid feeding device thus provides a swivel connection between the pipe sections 201 and 202 and is also actuated to produce a feeding action such as previously described, due to the movement of the base 209 relative to the casing 208, the base oscillating with the shaft 210 and the casing being stationary relative to the frame 191. The lubricant is thus fed from the base 209 through the conduit 212 to the bearings 211. The pipe section 202 is connected at the other end thereof with the base 213 of the fluid feeding member mounted on the other end of the arm 192, which base is fixed in position on said arm, a conduit 214 leading from said base to the ball and socket joint to lubricate the same. From the casing 215 of this last mentioned feeding device, the pipe 203 extends to the base 216 of another feeding device, (shown more in detail in Fig. 17), mounted at the forward end of the drag link in fixed position relative thereto, and the pipe 204 leads from the casing 217 thereof. Thus the feeding devices at opposite ends of the drag link serve as swivel connections between the pipe sections 202 and 203 and the pipe sections 203 and 204 respectively and feed lubricant to the bearings at opposite ends of the drag link. While the fluid feeding devices described above are shown as being provided with one pipe connection leading into the casing and the other into the base portion thereof, any type of feeding means with any one of the feeding mechanisms described herein may be used between the pipe sections, the type used being dependent upon what may be necessary to obtain the desired feeding action and the desired connection between the pipe sections.

Referring now to Fig. 15, the pipe section 204 is connected with the base 223 of the next feeding device by means of the union 218 and the pipe 207 is similarly connected with said base by means of the union 219. In order to obtain the desired movement of the casing 220 relative to the base to produce the feeding action of the device the arm 221 is provided thereon, which is connected through the spring 222 with the steering knuckle 199. Thus relative movement of the yoke 197 and the knuckle 199 will cause the said feeding device to feed lubricant to the bearing in the member 197 for the pin 224 rotating with the knuckle 199. In this case no swivel for the pipe line was needed and accordingly no feeding device of the type that acts as a swivel was used. The pipe 207 is connected at the other end thereof with the casing 225 of a feeding device, the base 226 of which is mounted on the pin 224 and from which a conduit 227 leads to the upper bearing for said pin in the yoke 197.

The lubricant is supplied from the reservoir 190 to the various pipe sections at a very low pressure, and may be supplied by gravity. Thus the oil pressure in the pipe sections 201, 202, 203, 204, 205, 206 and 207 is very low, and may be less than one pound, if desired. The various feeding devices supply the lubricant to the various bearings at a much higher pressure, however, and this may be varied according to the conditions encountered as desired, by variation in proportions of the internal mechanism of the feeding device, such as the strength of the spring and the cross sectional size of the plunger used. In a similar

manner the quantity fed with each feeding movement of the plunger may be varied, by adjusting the effective stroke of the plunger. In any case, however, the feeding is in proportion to the 5 relative movement of the parts carrying the base and casing members, or the parts with which said members are connected to produce relative movement between said casing and base.

A plurality of different parts to be lubricated 10 may thus be supplied from a single central reservoir at a low pressure and the lubricant fed there-to at different rates and at different much higher pressures dependent upon the pressure and quantity of lubricant needed. This is illustrated dia- 15 grammatically in Fig. 18, in which the pipe line made up of the sections 230, 231, 232, 233, 234 and 235 supplies lubricant at a low pressure, of say less than one pound, to the feeding devices 236, 237, 238, 239, 240 and as many more as may 20 be desired, and the feeding devices are so constructed and adjusted that the feeding device 236 supplies two drops per hour to the parts it lubricates at a pressure of 1500 pounds per square inch, while the feeding device 237 supplies forty 25 drops an hour to the parts it lubricates at a pressure of 2500 pounds per square inch. In a similar manner the feeding device 238 may be provided to supply forty drops per hour at 150 pounds per square inch, the device 239 thirty 30 drops per hour at fifty pounds per square inch and the device 240 two drops per hour at 500 pounds per square inch. These quantities and pressures are merely illustrative, but by proper arrangement and adjustment of the feeding 35 mechanisms described above this range of pressure and quantity can be obtained with said feeding devices, and the supply of fluid will be supplied at the same low substantially uniform pressure to said feeding devices. One particu- 40 larly great advantage of this arrangement is that the presence of any small, or even relatively large, leaks in the pipe line will not put the feeding devices out of operation as is the case where the lubricant is fed under a high pressure through 45 the pipe line to the parts to be lubricated.

Having thus described our invention what we desire to claim and secure by United States Letters Patent is:

1. The combination with a plurality of parts to 50 be lubricated of means for lubricating said parts comprising a lubricant reservoir, independently actuated feeding devices for supplying lubricant at a high pressure to said parts, and means for supplying lubricant from said reservoir at low 55 pressure to said feeding devices.

2. The combination with a plurality of parts to 60 be lubricated of individual feeding devices associated with said parts, a lubricant reservoir, a pipe line supplying lubricant from said reservoir to said feeding devices, and means for actuating 65 said feeding devices independently of each other and independently of the pressure of the lubricant in said pipe line.

3. The combination with a plurality of parts to 70 be lubricated, of means for lubricating said parts comprising a lubricant reservoir, feeding devices for supplying lubricant at a high pressure to said parts, each of said feeding devices operating independently of all the other feeding devices, 75 and means for supplying lubricant from said reservoir at low pressure to said feeding devices.

4. The combination with a plurality of parts to 80 be lubricated, of a lubricant reservoir, a low pressure pipe line leading from said reservoir and independently actuated lubricant feeding 85

devices for supplying lubricant at a higher pressure to said parts, interposed in and supplied with lubricant by said pipe line.

5. The combination with a plurality of parts to be lubricated, of a lubricant reservoir, a low pressure pipe line leading from said reservoir and lubricant feeding devices for supplying lubricant at a higher pressure to said parts, interposed in and supplied with lubricant by said pipe line, each of said feeding devices being operated independently of the other feeding devices whereby said feeding devices are adapted to supply different predetermined quantities of lubricant at different predetermined pressures to said parts.

6. The combination with a plurality of parts to be lubricated and comprising pairs of relatively movable members, of means for lubricating said parts comprising a lubricant reservoir, feeding devices for supplying lubricant at high pressure to said parts, each of said feeding devices comprising a reciprocable means and means for reciprocating the same comprising a clutch mechanism connected with one of said relatively movable members of each pair and operating to move said reciprocable means upon slight relative movement of said members, and means for supplying lubricant at relatively low pressure to said lubricating devices from said reservoir.

7. The combination with a pair of relatively movable members having engaging surfaces, of means for lubricating the engaging faces of said members comprising a lubricant reservoir, a feeding device for supplying lubricant at high pressure to said members, each comprising a ball clutch mechanism connected with one of said members and operating to move said reciprocable means upon slight relative movement of said members, and means for supplying lubricant to said feeding device from said reservoir at a relatively low pressure.

8. The combination with a plurality of movable parts to be lubricated, of means for lubricating said parts comprising a lubricant reservoir, individual feeding devices associated with said parts, each feeding device being controlled to feed lubricant at high pressure to the parts with which the same is associated by the movement of said parts, and means for supplying lubricant at relatively low pressure to said lubricating devices from said reservoir.

9. The combination with a plurality of movable parts to be lubricated, of means for lubricating said parts comprising a lubricant reservoir, individual feeding devices associated with said parts, each feeding device being independently controlled to feed lubricant at high pressure to the parts with which the same is associated by the movement of said parts, and means for supplying lubricant at relatively low pressure to said lubricating devices from said reservoir.

10. The combination with a pair of relatively movable members having engaging surfaces, of means for lubricating the engaging surfaces of said members, comprising a lubricant reservoir, a feeding device for supplying lubricant at high pressure to said surfaces comprising controlling means actuated by relative movement of said movable members, and a conduit for supplying lubricant from said reservoir to said feeding device at a relatively low pressure.

11. The combination with a plurality of pairs of relatively movable parts to be lubricated, of a lubricant reservoir, a low pressure pipe line leading from said reservoir, independent individual lubricant feeding devices for each pair of

movable parts interposed in and supplied with lubricant by said pipe line, and means for independently controlling the feeding movements of said feeding devices by the relative movement of 5 the pair of parts with which each feeding device is associated.

12. The combination with a plurality of pairs of relatively movable parts to be lubricated, of a lubricant reservoir, a low pressure pipe line leading 10 from said reservoir, independent individual lubricant feeding devices for supplying lubricant at high pressure to each pair of movable parts interposed in and supplied with lubricant by said pipe line, and means for independently controlling 15 the feeding movements of said feeding devices by the relative movement of the pair of parts with which each feeding device is associated.

13. The combination with a plurality of parts 20 to be lubricated, of means for lubricating said parts comprising a lubricant reservoir, independently actuated feeding devices, means for supplying lubricant at low pressure to said feeding devices from said reservoir, each feeding device being provided with means for controlling the feeding movement thereof entirely independent of all 25 the other feeding devices, and of the pressure at which the lubricant is supplied to said feeding devices.

14. In a lubricating system, a reservoir, a low pressure conduit extending from said reservoir, comprising relatively movable sections, high pressure lubricant feeding devices interposed between the sections of said conduit and supplied with lubricant from said low pressure conduit, and means for actuating said feeding devices controlled by the relative movement of adjoining sections of said conduit.

15. In a lubricating system, a reservoir, a low pressure conduit extending from said reservoir, comprising relatively movable sections, and high pressure lubricant feeding devices supplied with lubricant by said conduit interposed between the sections of said conduit, comprising means for swivelly connecting adjoining sections thereof.

16. In a lubricating system, a reservoir, a low pressure conduit extending from said reservoir, comprising relatively movable sections, and high pressure lubricant feeding devices supplied with lubricant by said conduit interposed between the sections of said conduit, comprising means for swivelly connecting adjoining sections thereof, each of said feeding devices being actuated entirely independently of all the other of said feeding devices.
